PNEUMATIC TUBE TERMINAL FOR REMOTE BANKING

Ross Cook, Rolling Hills, and Donald Keith Polgreen,
Los Angeles, Calif., assignors to Ross Cook, Inc., Los
Angeles, Calif., and said Polgreen, fractional part
interest to each

Filed June 14, 1974, Ser. No. 479,359

Term of patent 14 years

Int. Cl. D6—04

U.S. Cl. D31—22

FIG. 1.

FIG. 4.

FIG. 2.

FIG. 3.

FIG. 5.

FIG. 1 is a top plan view of a pneumatic tube terminal for remote banking incorporating our new design.

FIG. 2 is a front elevational view thereof with the front cover in its open position.

FIG. 3 is a side elevational view thereof, the opposite side being a mirror image.

FIG. 4 is a front elevational view thereof with the front cover in its closed position.

FIG. 5 is an exploded perspective view thereof.

We claim:

The ornamental design for a pneumatic tube terminal for remote banking, substantially as shown.
